(57) **CLAIM**

We claim the ornamental design for a multifunction printer, as shown and described.

DESCRIPTION

FIG. 1 is a front perspective view of a multifunction printer showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof;

FIG. 9 is an enlarged view of the encircled portion in FIG. 1;

FIG. 10 is an exploded view thereof; and,

FIG. 11 is another exploded view thereof.

The outermost evenly spaced broken lines immediately adjacent to the full line showing the claimed design represent the bounds of the claimed design while all other evenly spaced broken lines are directed to environment. The broken lines form no part of the claimed design.

The dot-dash broken lines encircling portions of the claimed design that are illustrated in enlargements form no part of the claimed design.

The lettering and icon forming part of the disclosure is a registered trademark of HP HEWLETT PACKARD GROUP LLC.

(Continued)

The multifunction printer shown in FIGS. 10 and 11 has been reduced in size proportionally and dimensionally in order to accommodate the exploded views that are shown.
